(57) **CLAIM**

The ornamental design for a snowthrower housing, as shown and described.

DESCRIPTION

FIG. 1 is a top left front perspective view of a snowthrower housing in accordance with the claimed design and shown in connection with a snowthrower;

FIG. 2 is a top right rear perspective view of the design and snowthrower of FIG. 1;

FIG. 3 is a top left front perspective view of the design of FIG. 1;

FIG. 4 is a top right rear perspective view of the design of FIG. 1;

FIG. 5 is a front elevation view of the design of FIG. 1;

FIG. 6 is a rear elevation view of the design of FIG. 1;

FIG. 7 is a left side elevation view of the design of FIG. 1;

FIG. 8 is a right side elevation view of the design of FIG. 1; and,

FIG. 9 is a top plan view of the design of FIG. 1.

The bottom plan view of the design is omitted as it forms no part of the claimed design and/or is cumulative in view of the remaining figures.

The dash-dash broken lines in the figures (including, e.g., handles, fasteners and openings for receiving such fasteners, etc.) represent unclaimed subject matter and form no part of the claimed design.

The dot-dash broken lines in the figures immediately adjacent solid lines represent a boundary between claimed and unclaimed subject matter and form no part of the claimed design.

1 Claim, 9 Drawing Sheets
